UNITED STATES PATENT OFFICE.

DANIEL S. TROY, OF MONTGOMERY, ALABAMA.

GAS-ENGINE.

SPECIFICATION forming part of Letters Patent No. 317,892, dated May 12, 1885.

Application filed July 30, 1884. (No model.)

To all whom it may concern:

Be it known that I, DANIEL S. TROY, of 5
Montgomery, in the county of Montgomery
and State of Alabama, have invented a new
and improved Gas-Engine, of which the fol-
lowing is a full, clear, and exact description.

The object of my invention is to provide a
new and improved engine which is operated
by the explosion of a mixture of compressed
10 gas and air, and also by the expansion of com-
pressed gas, which engine is so constructed
that it automatically provides itself with the
quantity of air required to produce the ex-
plosive mixture.

15 The invention consists in a gas-engine con-
structed with two cylinders, each containing
a separate piston connected with the same
crank-shaft, and with channels, tubes, or other
conductors by which compressed gas is con-
20 ducted into one cylinder, and after the gas
has expanded in the said cylinder it is mixed
with air and then conducted into the second
cylinder, in which the mixture is exploded,
thereby driving the piston forward, the piston
25 in the other cylinder being driven forward
by the expansion of the compressed gas. A
mixing-chamber is provided in which the gas
and air are mixed and then conducted into the
explosion-chamber. An automatic valve is
30 provided for admitting the mixture of gas and
air into the explosion-cylinder, and an auto-
matic lighting or spark-producing device for
igniting the mixture of gas and air is also pro-
vided, all as hereinafter full described, and
35 pointed out in the claims.

Reference is to be had to the accompanying
drawings, forming part of this specification,
in which similar letters of reference indicate
corresponding parts in all the figures.

40 Figure 1 is a side elevation of my improved
gas-engine, parts being broken out and others
shown in section. Fig. 2 is a longitudinal sec-
tional elevation of the same through the cyl-
inders. Fig. 3 is an enlarged cross-sectional
45 elevation of one of the cylinders and the regu-
lating-valves of the same. Fig. 4 is an en-
larged detail plan view of the under side of
one pair of cylinders. Fig. 5 is a sectional
plan view, looking upward, on the line $x-x$,
50 Fig. 3. Fig. 6 is a like sectional plan view
on the line $y-y$, Fig. 3. Fig. 7 is an enlarged
detail side view of the cam device for operat-

ing the valve for regulating the admission of
gas. Fig. 8 is an enlarged side view of the
cam mechanism for operating the additional 55
slide-valves for admitting the mixture of gas
and air into the chamber. Fig. 9 is a cross-
sectional view on the line $v-v$, Fig. 8.

The engine is constructed with two concen-
tric cylinders of which one surrounds the 60
other. I have shown two pairs of such con-
centric cylinders and pistons and suitable
connecting-rods connected with one shaft for
the purpose of overcoming the dead-center, the
engine shown being specially adapted for use 65
as a marine engine. As both pairs of cylin-
ders and the pistons, connecting-rods, valves,
&c., connected with the same are alike, I will
describe only one pair of cylinders and the de-
vices connected with the same.

70 For each pair of cylinders the shaft A is
provided with three cranks—namely, one
crank A' and two cranks A², the crank A'
projecting in a direction directly opposite to
that in which the cranks A² project, and be-
ing arranged between the cranks A²—that is, 75
the cranks A' and A² are one hundred and
eighty degrees from each other. The crank
A' is connected by a connecting-rod, B', with
a piston-rod, C', secured to a piston, D', work-
ing in a cylinder, E'. The cranks A² are con-
nected by connecting-rods B² with piston-rods
C², both secured to an annular piston, D²,
working in a cylinder, E², surrounding the
cylinder E'. The cylinder E' is closed at the
85 top and bottom and is provided with a suit-
able stuffing-box, E³, through which the pis-
ton-rod C' passes. The outer annular cylinder,
E², is open at the bottom. Cross-heads are
80 formed on the outer ends of the piston-rods C'
and C², the said cross-heads being guided by
suitable vertical guides held in the frame of
the machine.

90 In the upper part of the cylinder E² a cham-
ber, F, is formed between the top of the cyl-
inder and a horizontal partition, E⁴. In the
said chamber F a vertical cylinder, F', is ar-
ranged, in which a vertically-sliding valve,
F², is placed, which is adapted to close a chan-
nel, f, which is adapted to establish com-
munication between the cylinder E' and the
chamber F by means of the cylinder F', ar-
ranged in the said chamber F. The valve F²
is secured on a stem, f', projecting through a
100

stuffing-box in the top of the chamber F, and provided at its upper end with a head, f^2 . Between the head f^2 and the top of the cylinder a spring, f^3 , surrounds the stem f' and 5 presses the same upward. A lever, G, pivoted on the standard G' on the top of the cylinders has one end resting on the head f^2 of the stem f' and the other end resting on a rod, H, projecting down through a stuffing-box into 10 the middle of the upper part of the cylinder E', the said stuffing-box being arranged in the head of the said cylinder.

The rod H is provided at its upper end with a cross-pin to prevent it from dropping through 15 the stuffing-box into the cylinder. An electrical contact-piece, g, is held on that end of the lever G resting on the rod H, the said piece being insulated from the lever and connected by a wire, g' , with an electric lighter, I, in the 20 top of the cylinder for producing sparks, the lighter being connected by a wire, h , with an induction-coil, J, which is connected by a wire, i, with an arm, G', held on the top of the cylinder and insulated from the same. The free 25 end of the said arm G' is located above the contact-piece g on the lever G and carries a contact-screw, j.

On one side of each pair of cylinders E' and E² a valve box or chest, K, is formed, in 30 which two cylindrical chambers, L' and L², are formed, one above the other, and parallel with and adjoining the said chambers L' and L² two chambers, M' and M², are provided, which are also arranged one above the other, 35 the chambers M' M² being arranged between the outer cylinder, E', and the chambers L' L². The cylindrical chamber L' is connected with a pipe, N, for conducting the compressed gas from a receptacle into the said chamber L', 40 and the chamber L² is connected with a pipe, L, through which the air required is drawn into the chambers and then into the cylinders. The chamber M² is connected with a pipe, M, through which the exhaust-gases, &c., are 45 ejected from the cylinder E'. The chamber L' is connected by a channel, O', with the chamber M', and the chamber L² is connected by a channel, O², with the chamber M', which in turn is connected by a channel, P, with the 50 chamber F, and by a channel, Q, with the upper end of the exterior cylinder, E'. A check-valve, P', which opens into the chamber F, is arranged at the upper end of the channel P to prevent the gas and air in the chamber F 55 from passing back into the chamber M'. The chamber M² is connected by a channel, O³, with the upper part of the inner cylinder, E'.

A channel, O⁴, extends from about the middle of the chamber L² to the bottom of the 60 valve-box K, and is connected with the pipe Q', which is connected with the bottom of the cylinder E'. The end of the channel O' in the chamber L' and the end of the pipe N are arranged directly opposite each other and can 65 both be closed by a cylindrical valve, a, fitting closely in the chamber L' and mounted on a rod, R, projecting through the bottom of

the chamber L' and through the partitions separating the chambers L' and L².

Within the chamber L² a slide-valve, b, is 70 mounted on the rod R, the said valve being of less diameter than the chamber L², and being provided at each end with a head, d, fitting closely in the chamber, the valve b being of such length that when the lower head, d, closes the 75 channel O² the upper head, d, will be above the lower end of an enlargement, L³, formed in the upper part of the chamber L², thus permitting the air to pass from the enlargement L³ into the channel O⁴, and at the same time that the 80 channel O² is opened the upper head, d, will close the communication between the enlargement L³ at the upper part of the chamber L² and the channel O⁴.

The valves in the chambers M' and M² are 85 arranged on a rod, S, on the upper end of which a cylindrical valve, r, is mounted within the chamber M², and within the chamber M' a cylindrical valve, s, is mounted on the rod S, which valve s is of less diameter than 90 the chamber M', and is provided at each end with a head, t, fitting closely in the chamber. The lower end of the rod S is connected by a rod, S', with a shaft, S², one end of which is connected by a rod, S³, with a handle-lever, 95 S⁴, which can be locked in place in a notched disk, S⁵, on the frame of the machine, and on the same end of the shaft S² a downwardly-projecting rod, T, is formed, in the lower end of which a pin, T', is held, which projects into 100 a slot, u', in the head of a T-shaped lever, U, pivoted by a bent rocking pivot, T², on a standard, T³.

To the lower end of the downwardly-projecting arm or lever U a rod, V, is pivoted, 105 which is provided on the opposite end with a pin, V', which passes into a cam-groove, V², in a cam, V³, mounted on the shaft A, the said rod V being suitably guided in the frame of the machine. 110

The lower end of the rod R is pivoted to a lever, R', on a standard, R². A lever, R³, pivoted to the upper end of the standard R², is connected by a link, R⁴, with the lever R', thus keeping the levers R³ and R' parallel at all 115 times.

A rod, W, guided on the standard R², can slide vertically, and is provided at its lower end with a crank-pin, W', which projects into a cam-groove, W², in the side of a cog-wheel, 120 W³, which cog-wheel engages with a wheel, m, mounted on the shaft A, and having cogs on half its circumference. The length of the cogged part of the wheel m is equal to one-quarter of the circumference of the wheel W³. 125

The rod W is provided with two longitudinally-slotted arms, n and o, projecting in opposite directions, in which arms pins n' and o', respectively, are held to slide, the said pins being secured to rods n² and o², which are pivoted to the ends of angle-levers p and q, respectively, which levers can be locked on notched segmental or semicircular frames p' and q', respectively, the said frames being se- 130

cured to the frame of the machine. A spiral spring, w , surrounding the rod R , rests on a cross-piece or collar, w' , on the same and presses the same downward.

5 The operation is as follows: The cranks of one engine of the pair that act on the same shaft are arranged at right angles to the cranks on the other engine, so that when one engine is at the end of the stroke the other will be at the half-stroke. The chamber F must at all times be filled with a mixture of gas and air. As shown in Fig. 3, the piston D' in the cylinder E' moves downward. At the same time the ring-piston D^2 moves upward. When the piston D' moves upward, it creates a vacuum in the lower part of the cylinder E' , whereby the air is drawn through the pipe Q' and the channel O^4 , the chamber L^2 , and the pipe L , the valve b being so adjusted that its upper head, d , is above the bottom of the enlargement L^3 in the chamber L^2 , thus permitting the air to pass from the enlargement L^3 into the channel O^4 and thence into the cylinder. The ring-piston D^2 is moved downward by 25 the expansion of the compressed gas in the outer cylinder, E^2 , which gas passes from the pipe N to the chamber L' , the channel O' , the chamber M' , and the channel Q , the valve a being so adjusted as to permit the gas to pass from the pipe N directly into the channel O' , and the valve s being so adjusted that its upper head, t , prevents communication between the channels P and Q , but establishes communication between the channels O' and Q by means of the chamber M' . When the piston D' strikes the lower end of the rod H , it forces the same upward, thereby causing the lever G to press down the valve F^2 and permit the charge of gas and air in the chamber F to pass into the upper part of the cylinder E' , the contact-piece g is brought in contact with the contact-piece j , the circuit is closed, a spark is produced by the lighter or other devices, I , and the mixture of gas and air in the upper part of the cylinder E' is exploded and forces down the piston D' with great force, the spring f^3 , which has been compressed by the lever G , expands, thereby forcing the valve F^2 upward to close the channel f and at the same time forcing the rod H down. As the piston D' moves downward it forces the air between the bottom of the cylinder and the piston through the tube Q , the channel O^4 into the chamber L^2 , the channel O^2 into the upper part of the chamber M' , and through the channel P into the chamber F . At the same time the ring-piston D^2 is moved upward from the crank-shaft and forces the gas in the cylinder E^2 through 55 the channel Q into the chamber M' , and from there into the channel P and the chamber F , the valve s being so arranged that its lower head closes the channel O' , and the lower head, d , of the valve b closes the channel O^2 . 60 When the piston D' rises again, it forces out the products of explosion and the above described operation is repeated.

By the expansion of the compressed gas in the outer cylinder, E^2 , the walls of the inner cylinder, E' , in which the explosion takes place, are cooled.

The slide-valves s r are operated from the T-shaped rocking lever U by means of the connecting-rod S' .

By means of the lever S^4 and the connecting-rod S^3 the positions of the connecting-rod S' and the rod S can be changed, and thus the position of the valves reversed and the movement of the engine reversed.

As the movement of the valves a b must be 80 very rapid, the cam-tracks W^2 and the wheel W^3 have been arranged in a corresponding manner.

There is one explosion which takes place in the cylinder E' for each stroke of each engine, 85 and the valves a b , for admitting the gas and air, must be shifted once for each stroke. This is accomplished by means of the cog-wheel m , which during half its revolution revolves the wheel W^3 one-quarter of a revolution, and as 90 the cam W^2 is provided with four curves, as shown, the valves a b will be shifted once for each quarter-revolution of the wheel W^3 —that is, for each revolution of the shaft A . The rod W is reciprocated by the cam, and the pin 95 n' in the arm n strikes against the lever R^3 , thus moving the rod R upward, which is moved downward again by the spring w . When the engine is reversed, the pin o' in the arm o of the rod W strikes the lever R' , thereby moving the rod R upward. The distance that the levers R^3 and R' are moved depends upon the positions of the pins o' and n' , which can be adjusted by means of the levers p and q , and thereby a greater or less quantity of compressed gas and air can be admitted into the chamber F or the cylinder E' .

I have shown my improved gas-engine constructed as an upright engine; but it can as well be constructed as a horizontal engine. 110 The special features of the engine are that for each revolution of the shaft one explosion takes place, which drives the central or inner piston downward, which piston is then carried upward by the impetus of the shaft, and when 115 the inner piston moves upward the outer piston is moved downward by the expansion of the compressed gas, thereby cooling the inner cylinder. The inner piston at the same time acts as an air-pump to provide the required quantity of air to produce the explosive mixture of gases.

Having thus described my invention, what I claim as new, and desire to secure by Letters Patent, is—

1. A gas-engine constructed with two independent cylinders, each containing an independent piston, both pistons being adapted to act upon the same shaft, and with pipes, channels, or other conductors for conducting compressed gas into one cylinder, and then conducting the gas after it has expanded into the second cylinder to be exploded, the first-mentioned cylinder being open at one end and

the second-mentioned cylinder being closed at both ends, substantially as herein shown and described.

2. In a gas-engine, the combination, with a cylinder open at one end and a cylinder closed at both ends, of pistons in the said cylinders, channels, tubes, or other conductors for conducting gas into the open cylinder, and from the same into the closed cylinder, and of a pipe for conducting air into one end of the closed cylinder, substantially as herein shown and described.

3. A gas-engine constructed with a cylinder which is open at one end and a cylinder closed at both ends, pistons in the cylinders, pipes, channels, or other conductors for conducting compressed gas into the open cylinder and from the same into the closed cylinder, and a pipe connected with the bottom of the closed cylinder and placed in communication with channels, pipes, or other conductors for conducting the air from the closed cylinder into a chamber with the gas that has been conducted out of the open cylinder, substantially as herein shown and described.

4. In a gas-engine, the combination, with a cylinder open at one end, a cylinder closed at both ends, and a gas-chamber, of a piston in each cylinder, and of tubes, channels, or other

conductors for conducting compressed air into the open cylinder, from the said open cylinder into the gas-chamber, and from the gas-chamber into the closed cylinder, substantially as herein shown and described.

5. In a gas-engine, the combination, with a cylinder open at one end, a cylinder closed at both ends, and a gas-chamber, of a piston in each cylinder, channels, tubes, or other conductors for conducting compressed gas into the open cylinder, and from the same into the gas-chamber, and from the gas-chamber into the closed cylinder, and tubes, channels, or other conductors for conducting air from the closed cylinder into the gas-chamber, substantially as herein shown and described.

6. In a gas-engine, the combination, with a cylinder open at one end, a cylinder closed at both ends, and a gas-chamber, of a piston in each cylinder, a shaft having directly-opposite cranks, with which the piston-rods of the two cylinders are connected, channels, tubes, or other conductors for conducting compressed gas into the open cylinder, channels for conducting the gas from the open cylinder into the gas-chamber, and channels for conducting the gas from the gas-chamber into the closed cylinder, substantially as herein shown and described.

7. In a gas-engine, the combination, with a cylinder open at one end and a cylinder closed at both ends, of pistons in the cylinders, which pistons are connected with the opposite cranks of a crank-shaft, so that the said pistons will be moved in opposite directions, pipes, channels, or other conductors for conducting compressed gas into the open cylinder, and chan-

nels, pipes, or other conductors for conducting the gas after it has expanded in the open cylinder into the closed cylinder, substantially as herein shown and described.

8. In a gas-engine, the combination, with a cylinder open at one end and a cylinder closed at both ends, of pistons in the said cylinders, the said pistons moving in opposite directions, pipes or other conductors for conducting compressed gas into the open cylinder, and after it has expanded from the same into the closed cylinder, and an automatically-operating device for admitting the gas and air mixed within the gas-chamber into the said closed cylinder when the piston in the said closed cylinder is near one end of the said cylinder, substantially as herein shown and described.

9. In a gas-engine, the combination, with a cylinder open at one end and a cylinder closed at both ends, of pistons in the said cylinders, the said pistons moving in opposite directions, pipes or other conductors for conducting compressed gas into the open cylinder, and after it has expanded in the same into the closed cylinder, an automatically-operating device for admitting gas and air mixed in the gas-chamber into the said closed cylinder when the piston in the closed cylinder is near one end of the said cylinder, and an automatic device for producing a spark by closing an electric circuit, or in any other suitable manner, directly after the mixture of gas and air has been admitted into the closed cylinder, substantially as herein shown and described.

10. In a gas-engine, the combination, with two cylinders connected by suitable channels, of a piston in each cylinder, and two sets of valves for admitting gas and air into a gas-chamber connected with one of the cylinders, substantially as herein shown and described.

11. In a gas-engine, the combination, with two cylinders, of pistons in the same, and of slide-valves for admitting gas into one cylinder and air into the other, and admitting the mixture of gas and air into the latter cylinder, substantially as herein shown and described.

12. A gas-engine constructed with two concentric cylinders, above the outer one of which a gas-chamber is formed, substantially as herein shown and described.

13. A gas-engine constructed with two concentric cylinders, on the outer one of which a gas-chamber and a valve chest or box are formed, substantially as herein shown and described.

14. A gas-engine constructed with two concentric cylinders, a gas-chamber, a valve-box, and with a pipe connecting one end of the inner cylinder with the valve-box, substantially as herein shown and described.

15. In a gas-engine, the combination, with the concentric cylinders E' E², above the latter of which a gas-chamber, F, is formed, of the valve F², the valve-stem f', the pivoted lever G, the sliding rod H in one end of the

inner cylinder, E', and the pistons D' and D² in the cylinders E' and E², substantially as herein shown and described.

16. In a gas-engine, the combination, with 5 the concentric cylinders E' E², of which the latter forms a gas-chamber, F, of the valve F², the valve-stem f', the lever G, the sliding rod H in the end of the cylinder E', the contact g, secured on one end of the lever G and 10 connected with an electric lighter, I, the arm G', the contact j on the same, an induction apparatus connected with the said contacts, and of the pistons D' D² in the said cylinders, substantially as herein shown and described.
- 15 17. In a gas-engine, the combination, with the cylinders E' E², of which the latter forms the gas-chamber F, of the pistons D' D², the valve-box K, the valves a b, mounted on the

valve rod R, and the valves r s, mounted on a valve-rod, S, the pipe Q, connecting a channel in the valve-box with the cylinder E', and devices for operating the valve-rods from the shaft, substantially as herein shown and described.

18. The herein-described method of cooling 25 the explosive-cylinder of a gas-engine, consisting in conducting compressed gas into a cylinder surrounding the said explosive-cylinder, whereby the walls of the latter will be cooled by the expansion of the compressed 30 gas, as set forth.

DANIEL S. TROY.
